(57) **CLAIM**

The ornamental design for a container for food items, as shown and described.

DESCRIPTION

FIG. 1 is a top perspective view of a container for food items;

FIG. 2 is a bottom perspective view of the container of FIG. 1;

FIG. 3 is a top plan view of the container of FIG. 1;

FIG. 4 is a bottom plan view of the container of FIG. 1;

FIG. 5 is a left side view of the container of FIG. 1;

FIG. 6 is a right side view of the container of FIG. 1;

FIG. 7 is a front side view of the container of FIG. 1;

FIG. 8 is a rear side view of the container of FIG. 1;

FIG. 9 is a view from above illustrating the container of FIG. 1 in the open configuration; and,

FIG. 10 is a plan view from above illustrating the container of FIG. 1 in the open configuration.

The broken lines shown in the drawings are for illustrative purposes only and do not form part of the claimed design.

1 Claim, 10 Drawing Sheets
